Ross Woodward. BY Richard Oliver.

ATTORNEY

UNITED STATES PATENT OFFICE.

HENRY F. KOCH, OF ST. LOUIS, MISSOURI.

PORTABLE BUILDING.

1,258,788.

Specification of Letters Patent. Patented Mar. 12, 1918.

Application filed January 17, 1917. Serial No. 142,889.

To all whom it may concern.

Be it known that I, HENRY F. KOCH, a citizen of the United States, residing at St. Louis, State of Missouri, have invented certain new and useful Improvements in Portable Buildings, of which the following is a specification.

This invention relates to an improved toy building and the principal object of the invention is to provide a toy building which is of the knock-down type and may be contained in a suitable box which when the building is set up will form the foundation and support for the building.

Another object of the invention is to so construct this toy building that the walls, roof and porch may be releasably connected by means of pins thus permitting the building to be easily and quickly put together and securely held in a set-up position.

Another object of the invention is to so construct this building that the window frames may be releasably held in place and to further so construct these frames that glass or other transparent sheets may be placed in the frame.

Another object of this invention is to so construct the building that when taken to pieces, it may be packed in the box and form a compact mass preventing movement in the box which would be liable to cause breakage.

This invention is illustrated in the accompanying drawings, wherein:

Figure 1 is a perspective view of the building in a set-up position.

Fig. 2 is a sectional view through one of the windows taken along the line 2-2 of Fig. 1.

Fig. 3 is a fragmentary view of one corner portion of the building taken along the line 3-3 of Fig. 1.

Fig. 4 is a view showing the improved building in rear elevation.

Fig. 5 is a perspective view of the doors used in connection with the building.

Figs. 6 and 7 are perspective views showing windows used in connection with the building.

Fig. 8 is a longitudinal sectional view showing the building taken apart and packed in the box, forming the foundation and supports in Fig. 1, and

Fig. 9 is a transverse sectional view through the box and collapsed building.

Fig. 10 is a fragmentary perspective view

of a wall section showing the upper corner portion of a window opening.

The receptacle or box for containing the building when packed is provided with the two sections 10 which if desired may be used as a foundation for the set up building and will be of such size as to form a porch about the building as clearly shown in Fig. 1. When set up, the building will be provided with forward and rear walls 11 and 12, end walls 13, a roof having forward and rear sections 14 and 15 and a porch roof 16 supported by posts 17. The walls are provided at their adjoining edges with tongues rolled to provide sleeves or sockets 18 to receive the securing pins 19 thus releasably connecting the walls when in a set up position. The sections 14, 15 and 16 forming the roof of the building and the roof of the porch are also provided with sleeves or sockets 20 similar to the sockets 18 and receive pins 21 to pivotally connect these sections so that they may assume the position shown in Figs. 1 and 2 when in place and may also be folded as shown in Fig. 9 when the building is placed in the receptacle. A partition 22 is placed within the building and held in place by cleats 23 secured to the forward and rear walls, it being understood that if desired more than one partition may be put in place thus dividing the building into a plurality of rooms.

Therefore there has been provided a toy building in which the walls and roof may be releasably set up with the walls releasably connected and the roof formed in sections hingedly connected in order to permit the roof to be folded. In order to provide doors and windows, there has been provided door frames 24 provided at their outer edge portions with longitudinally extending sockets 25 to receive securing pins 26 passing through hinge ears or sockets 26 extending from the wall. The adjoining edges and lower edges of the doors are provided with flanges 27 which together with the tongues 28 form pockets to receive the glass 29. Therefore the doors may be hingedly mounted and may be opened and closed when so desired. The windows are provided with frames 30 which may be provided with cross bars dividing the window frames into sections representing glass receiving sections. These window frames are provided with sleeves or sockets 31 similar to

the sleeves 25 to receive the fastening pins 32 passing through the hinge ears or sockets 32' and serving to hold the window frames in place. These frames are further provided 5 with lower flanges or ledges 33 which together with the tongues 34 serve to hold the glass 35 in the frame. It is of course obvious that the windows will not swing outwardly as two pins are provided for each 10 window but that if it is desired to open the window for any reason this can be easily done by removing one of the pins 32.

This building can be easily and quickly set up and will remain securely in the set-up 15 position and is so constructed that if desired one section of the roof may be raised to obtain access to the interior of the building. When taking the building to pieces, it is simply necessary to remove the roof and 20 fold it as shown in Figs. 8 and 9 and to disconnect the walls by removing the securing pins 19. When packed as shown in Figs. 8 and 9, the portions forming the building completely fill the receptacle thus 25 preventing the sections of the building from moving in the receptacle. This construction further provides a convenient container for the building when not in use and further provides a construction which will permit

the receptacle to be used when the building is set up although it is not absolutely necessary to make use of the box or receptacle as a foundation when the building is in use.

What is claimed is:—

1. A portable building having a wall provided with an opening, sockets at the side edges of said opening, a closure for the opening provided with sockets extending in operative relation to the sockets of the wall, a retaining flange carried by said closure, retaining lugs extending from the sockets of said closure, plates carried by the closure and forming a transparent closure held in place by said retaining flanges and lugs.

2. A portable building having a wall provided with an opening, a frame positioned in said opening, and provided with retaining flanges and lugs, a transparent sheet carried by said frame and held in place by said flanges and lugs, and means releasably holding said frame within the opening.

In testimony whereof I affix my signature in presence of two witnesses.

HENRY F. KOCH.
